AUTOMOBILE LOCK

Filed Jan. 31, 1924

UNITED STATES PATENT OFFICE

HORACE T. THOMAS, OF LANSING, MICHIGAN

AUTOMOBILE LOCK

Application filed January 31, 1924. Serial No. 629,644.

My invention relates to automobile locks and especially to a construction by which the ignition circuit is broken when the mechanism is locked.

The accompanying drawings show my invention in connection with the apparatus patented to me September 12th, 1922, by United States Letters Patent No. 1,428,720, in which drawings:—

Figure 1 is a sectional view of an apparatus embodying my invention and so much of said patented device as is necessary to illustrate its connection therewith.

Figure 2 is a view similar to Figure 1, showing the parts in the position they assume when the lock is engaged.

Figure 3 is a detailed sectional view on the line III, III, Figure 2.

a is the casing for the change-speed gear 20 ing and a2 are the rods which shift the gears when operated by the gear shift lever which is not shown. These rods are slotted on their adjacent sides at a3.

c is a vertically reciprocating rod or locking plunger. b is a locking blade or bolt 25 pivotally secured at its upper end to the lower end of the rod c, and properly guided in its motion. e3 is a pedal on the upper end of the rod c. e2 is a slot cut into the rod c from one side thereof.

d is a bolt adapted to slide in ways at right angles to the bolt c which is pressed toward said bolt by a compression spring d3. d2 is a slot in the upper surface of the bolt d.

e is a lock casing screwed into an aperture 30 above the bolt d. e2 is the rotatable cylindrical part of a pinlock in the casing e, having a lug e3 extending downward from its lower end and engaging in the slot d2 in the bolt d.

g is a sleeve surrounding the rod c and adapted to turn about the axis of said rod. g2 is a shield which, at the unlocked position of the apparatus comes above the casing e 45 covering the keyhole of the pinlock. This sleeve has an aperture g3, (Figure 3), which when turned so as to remove the shield g2 from above the casing e, comes opposite the bolt d, and permits said bolt to engage the said rod c and enter the slot e2 when said

rod is depressed to engage the bolt b in the slots a3 to lock the change-speed gear in neutral position.

The above described apparatus is that of the above named patent.

h is a cylinder screwed into the wall enclosing the bolt d with its axis extending in a direction at right angles to the length of said bolt. f2 is a disc fitting and adapted to reciprocate in the bore of the cylinder h. f4 is a compression spring acting upon the disc f2 to force the same toward the upper end of the cylinder h. f is a contact piece extending through the upper end of the cylinder h and fastened at its lower end to the disc f2. In the unlocked position of the bolt d, the contact piece f is forced into engagement with the surface of said bolt by the spring f4, as illustrated in Figure 1.

d4 is a slot in the lower surface of the bolt d. In the position of the parts shown in Figure 2, in which the bolt b is engaged with the shifting rods a2 to lock the change-speed gear in neutral position, the bolt d is forced forward engaging in the slot e2, and holding the bolt b engaged in the slots a3. In this position of the bolt d the slot d4 comes just above the contact piece f and said contact piece enters said slot without touching the walls thereof, its motion being limited by the disc f2 engaging the upper end of the cylinder h.

f3 is a conductor forming a part of the ignition circuit. This conductor is connected electrically and mechanically to the disc f2 and contact piece f. When the bolt d is in its engaged position and the contact piece f enters the slot d4 without touching the walls thereof, as shown in Figure 2, the ignition circuit is broken.

The operation of the above described device is as follows:

When it is desired to lock the automobile the change-speed gear is thrown into neutral with the slots a3 in the shifting rods 95 opposite each other. The shield g2 is removed from over the casing e and turned 90 degrees, which brings the slot g3 of the sleeve g opposite the bolt d. The spring d3 then forces the bolt d forward, engaging 100

in said slot and in the slot *c2* and holding the rod *c* at the lower end of its travel, with the bolt *b* engaged in the slots *a3* of the gear shifting rods *a2*. At this position the slot *d4* comes just above the contact piece *f* which removes the bolt from contact with the contact piece *f* and breaks the ignition circuit. When it is desired to unlock the mechanism, a key is inserted in the slot of the pinlock and the cylinder *e2* is rotated, the lug *e3* engaging the wall of the slot *d2* and forcing the bolt *d* out of the slot *c2* and aperture *g3* in the sleeve *g*. This brings the surface of the bolt *d* into contact with the point *f* and completes the ignition circuit. The shield *g2* may now be rotated to the position shown in Figure 1 in which the wall of the sleeve is interposed between the bolt *d* and the plunger *c* holding said bolt in its retracted position with the circuit closed, which is the running position of the parts.

What I claim is:

1. In an apparatus of the kind described, the combination of a gear shifting rod, a plunger adapted to reciprocate to engage with and disengage from said rod, a bolt adapted to reciprocate to engage said plunger to hold it in engagement with said rod, an ignition circuit including said bolt, and a contact point so located in the ignition circuit that it shall engage said bolt to complete the circuit when said bolt is disengaged from said plunger and shall be out of engagement with said bolt to break said circuit when said bolt engages said plunger.

2. In an apparatus of the kind described having an ignition circuit, the combination of a gear shifting rod having a slot therein, a plunger provided with a slot adapted to reciprocate to enter the slot in said rod to lock the same and to withdraw from the same, a bolt adapted to reciprocate to engage in the slot in the plunger and withdraw from the same, and means whereby the engagement of said bolt shall break the ignition circuit.

In testimony whereof, I sign this specification.

HORACE T. THOMAS
